(57) **CLAIM**

The ornamental design for a cross connect block, as shown and described.

DESCRIPTION

FIG. 1 is a top view of a cross connect block showing our new design;

FIG. 2 is a side view thereof;

FIG. 3 is a front view thereof;

FIG. 4 is a bottom view thereof;

FIG. 5 is a another side view thereof;

FIG. 6 is a back view thereof; and,

FIG. 7 is a perspective view thereof.

The broken line portion of the figure drawings is included to show unclaimed subject matter only and forms no part of the claimed design.

1 Claim, 4 Drawing Sheets

FIG. 2

FIG. 5

FIG. 4

FIG. 6

FIG. 7
